(57) **CLAIM**

The ornamental design for an instrument panel for an automobile radio and navigation system, as shown and described.

DESCRIPTION

FIG. 1 is a perspective view of an instrument panel for an automobile radio and navigation system according to my novel design;

FIG. 2 is a front view of the instrument panel for an automobile radio and navigation system according to my novel design;

FIG. 3 is a right view of the instrument panel for an automobile radio and navigation system according to my novel design;

FIG. 4 is a bottom view of the instrument panel for an automobile radio and navigation system according to my novel design;

FIG. 5 is a top view of the instrument panel for an automobile radio and navigation system according to my novel design; and,

FIG. 6 is a left side view of the instrument panel for an automobile radio and navigation system according to my novel design.

The dash lines shown depict environment and are not part of my claimed design.
